United States Patent Office

Des. 213,545
Patented Mar. 18, 1969

213,545

BOTTLE OR SIMILAR ARTICLE

Victor Koenigsberg, Franklin Square, N.Y., assignor to Colgate-Palmolive Company, New York, N.Y., a corporation of Delaware

Filed Nov. 21, 1967, Ser. No. 9,491

Term of patent 14 years

U.S. Cl. D9—169
Int. Cl. D9—01

FIG. 1

FIG. 2

FIG. 3

FIG. 4

FIG. 5

FIG. 1 is a side elevational view of a bottle embodying my new design;

FIG. 2 is a side elevational view of a modified form thereof;

FIG. 3 is a bottom plan view of the bottle of FIG. 1;

FIG. 4 is a bottom plan view of the bottle of FIG. 2; and

FIG. 5 is a top plan view of the bottle of FIG. 1 with the top plan view of the bottle of FIG. 2 being the same in appearance.

The sides opposite those shown in FIGS. 1 and 2 are the same in appearance as the respective sides shown.

I claim:

The ornamental design for a bottle or similar article, as shown and described.
